UNITED STATES PATENT OFFICE.

EDGAR W. ANTHONY, OF BROOKLINE, MASSACHUSETTS.

COOKING STOVE OR RANGE.

SPECIFICATION forming part of Letters Patent No. 693,343, dated February 11, 1902.

Application filed December 13, 1900. Serial No. 39,687. (No model.)

To all whom it may concern:

Be it known that I, EDGAR W. ANTHONY, a citizen of the United States, residing at Brookline, in the county of Norfolk and State 5 of Massachusetts, have invented a new and useful Improvement in Cooking Stoves or Ranges, of which the following is a full, clear, and exact description, reference being had to the accompanying drawings, forming a part 10 of this specification, in explaining its nature.

The invention relates especially to the construction of the baking-oven and to provisions whereby its temperature is equalized and its effectiveness increased.

15 The invention will be described in connection with the drawings, wherein—

Figure 1 is a view in vertical section of a range having the features of my invention upon the dotted line 1 1 of Fig. 2, also showing in elevation the parts of the range back of said line. Fig. 2 is a view of the range in cross-section upon the dotted line 2 2 of Fig. 1. Fig. 3 is a view of the range in horizontal section upon the dotted line 4 4 of Fig. 1. 25 Figs. 4, 5, and 6 represent the hearth-plate and its rim or band.

The cooking stove or range has the ash-pit A, the fire-pot B, and ordinary flues common to the usual types of cooking stoves or 30 ranges. The bottom, top, and side walls of the baking-oven C are made of sheet metal, preferably in one piece. This produces a box-like structure open at both ends. It is attached to the stove or range in the following manner: One end is riveted to the flange c of the oven-door frame c', the door-frame being itself bolted or riveted in place to the side plate of the range. The inner end of the side walls has lugs or ears c², which extend at a 35 right angle to the walls. These lugs or ears preferably are of cast-iron and formed integral with the plates C' C², hereinafter referred to. The lugs or ears have holes through which are bolts or screws c³, extending through the 40 side plate c⁴ of the stove. The side plate c⁴ is formed, as represented in Fig. 3, to provide a shallow chamber c⁵ on its inner side, having the inclined or tapering edge or wall c⁶. The inner end of the sheet-metal walls is 45 rounded or turned inward somewhat, but is a little larger in size than the inner end of

the shallow chamber c⁵. The bolts or screws engaging the lugs or ears serve when tightened to draw toward the side plate c⁴ of the stove and into the shallow chamber the inner corners of the oven-walls against the inclined wall c⁶ of the side plate, causing the corners of the oven-walls to conform to and tightly hug or bear against the inclined wall to such an extent as to make a sufficiently 55 tight joint between the inner edge of the oven-walls and the side plate of the stove. The door-frame c' is at the same time drawn by the screws or bolts c³ to its seat against the side frame of the range. The lugs or 60 ears c² serve to receive the oven end plate D and to hold it separated from the side plate c⁴ sufficiently to create a dead-air space c⁷ between it and the side plate. The side plate may also be lined or covered upon 65 its inside with a sheet or layer of asbestos paper d or other non-heat-conducting material, and the dead-air space c⁷ and heat-deadening layer prevent conduction of heat from the oven through the side plate of the 70 stove. The metal plate D, which forms the inner end of the oven, is fastened at one end by the lugs d', extending from the plate, and at the other end by a tap-screw d², which screws into one of the ears or lugs c². This 75 end plate D preferably has its out or exposed side lined or surfaced with porcelain or similar material to provide a white polished illuminating-surface to reflect forward the heat of the oven in the oven-chamber and to disseminate and reflect in the oven-chamber the light striking against it when the oven-door is open, so that the back part of the oven is made attractive and visible and the end provided with a clean white finish which will 80 not rust or tarnish under any condition. The plates C' C² are cast-metal plates and are riveted or otherwise attached to the sheet-metal walls of the oven, and they are provided with ears or ledges for supporting an oven-shelf. 85 The plate C' is also a flue-forming plate, and it is attached by its outer end to the flanges c and c⁸ of the oven-door frame c'. (See Fig. 2.) Between the side wall e of the oven and the rear wall e' of the ash-pit there is an air-flue 90 E, having connection with the outer air at each lower corner by an air-inlet e², extend-

ing through the bottom of the range. (See Figs. 1 and 3.) The said air-flue E is connected, by means of holes e^3 in the side wall e , with an air-circulating flue or passage e^4 within 5 in the oven, formed by the cast-metal plate C'. This plate C' is of an angular shape—that is, it is formed to cover a large section of the side wall and of the top of the oven—and it is connected with the oven by the opening e^5 along its lower edge, and it opens into the oven by an outlet e^6 at its rear end. The plate is further fashioned to provide an enlargement e^7 of the flue or passage e^4 by being bowed outward into the oven, and this 10 bowed portion of the plate covers a considerable part of the upper central area of the side wall e . This increases the width of the flue or passage against the portion of the wall of the oven which is most liable to become 15 overheated and provides a larger air circulation against this portion of the wall, and thus tends to prevent the overheating of the plate e from overheating the oven. The operation of this part of the invention is 20 as follows: Air is drawn into the flue E through inlets e^2 and passes into the oven circulating flue or passage e^4 and through this passage about one side and a larger portion of the top of the oven to the outlet e^6 , where it enters the 25 oven. As the flue or passage e^4 also has an inlet e^5 from the oven, it follows that the circulation it provides not only supplies the oven with fresh air of uniform temperature, but also establishes a circulation through the oven 30 by causing air to be drawn from the oven through the inlet e^5 and to be mixed with the atmospheric air as it enters and passes through the flue e^4 . The flue e^4 establishes an air-space at the side of the oven toward the 35 fire-pot and at the top of the oven, which serves, in addition to its functions as a source of supply of fresh air to the oven as a circulating agent, to prevent the overheating of the oven by checking the conduction of heat from 40 the side wall and top of the oven. The cast-metal plate C' may have one or more small holes e^8 opposite the inlet-holes e^3 through the flue e^4 , through which air from the oven may enter the passage, and there may also be one 45 or more vent-holes e^9 in the back plate opening into the back flue.

I have shown in Fig. 2 a shelf construction comprising a shelf F, having an extension which is therein indicated in dotted and full 55 lines. This construction I do not describe in this application, as it forms part of my application for Letters Patent of the United States, Serial No. 72,867, filed August 22, 1901.

I have shown in Figs. 4, 5, and 6 a construction of a band or rim which, while as shown it is applied to a hearth, may be applied to a 60 stove-plate or other like portion of a stove. I will describe it here, however, as applied to a hearth-band for purposes of convenience 65 merely. Heretofore hearth-bands have been made in two parts, which abut at or near the front corner of the hearth and form a straight

joint, indicating at once that the band or rim had been formed of two pieces. This is objectionable because of this appearance and 70 because the joint collects dust and other matter. By my improvement, while the hearth-band is still made in two pieces, it has the appearance of being continuous or in one piece. This result is obtained by causing the corner 75 end h of one section H to be shaped along its outer end and to have its top adjacent to said end so formed as to provide a portion of a design h' and also by fashioning the abutting end h^2 of the other section H' of the band 80 to form a part of the entire design, the edge of which section H', with the edge of the corner h , constituting a line h^3 of the design. The said end of the second section may serve 85 to secure the corner of the first section in place to the stove by being shaped to form a sunken recess or support under which a lip 90 h^4 may extend or lap.

Having thus fully described my invention, I claim and desire to secure by Letters Patent 95 of the United States—

1. In a cooking stove or range, a side plate having a shallow chamber upon its inner side provided with inclined walls with a sheet-metal oven having a bottom, top and sides 95 and open at its back, slightly larger than the inner end of said chamber and of a shape to fit into the same, and connections between said side plate and the oven for drawing the sheet-metal oven into said chamber until its 100 inner edge or portions thereof are brought into close contact with the inclined walls of the chamber, as and for the purposes set forth.

2. In a cooking stove or range, a sheet-metal oven having its bottom, top and sides of a 105 single piece of metal, a cast-metal door-frame having a flange, means for connecting said flange with one end of the oven, a side plate having a shallow chamber upon its inner side provided with inclined walls and adapted to 110 receive the rear edge of the oven, and means for attachment of the oven thereto, whereby the rear edge of the oven will be caused to engage 115 inclined walls and make a tight joint therewith, as and for the purposes described.

3. In a cooking stove or range provided with a side plate having a shallow chamber on its inner side provided with inclined walls, an oven having its bottom, top and sides of one 120 piece of sheet metal and open at the back, lugs attached to its rear edge, means for attaching said lugs to said side plate and an end plate, and means whereby said end plate is held in place against said lugs and causes the 125 close engagement of the top, bottom and sides of the oven with the inclined walls of said shallow chamber, as described.

4. The combination in a cooking stove or range of a flue interposed between the front 130 wall of the oven and the ash-pit wall and connected with the outer air, a circulating passage or flue in the oven along its front wall and beneath its top having an inlet opening

from the oven, an outlet opening into the oven, the said flues being connected by holes or passages in the front wall of the oven.

5. In a cooking stove or range, an oven having a circulating-flue opening along the side of the oven toward the fire-pot and some distance removed from the bottom thereof, then extending along said side to within a short space of the top of the oven, then along the top and opening again into the oven at a point a short distance removed from its rear side diagonally across from the first-named opening, with a means for admitting air into the said flue to allow the same to mingle with the hot air of the oven rising into the said flue through the bottom opening, and to pass up through the said flue, and be distributed from the rear opening into the oven thus creating a continuous circulation therein.

20 6. In a cooking stove or range, an oven having sheet-metal sides, top and bottom, a door-casing to which one end of the sheet-metal oven is attached, an angular, cast-metal flue-forming plate secured to said door-casing in a manner to form a flue or passage between it and the front wall and top of the oven and having a lug at its inner end, a cast-metal plate attached to the rear side wall of the oven having at its inner end a lug, the side 25 plate of the stove having a shallow chamber with inclined walls, the inner end of which chamber is slightly smaller than the oven and means for drawing the oven toward and attaching it to said side plate and for fastening 30 the door-frame to the stove side.

35 7. In a cooking stove or range an oven, a plate located therein and forming in connection with that side of the oven toward the fire-box of the stove, and with the top of the oven, a circulating flue or passage, said flue or passage being increased in width where the wall of the oven is most liable to become overheated, and being provided with means whereby the outer air is fed into it at said

widest portion, as and for the purposes described.

8. In a cooking stove or range a side plate having a shallow chamber provided with inclined walls on its inner side, a sheet-metal oven having bottom, top and sides adapted 50 to engage at its rear edge the inclined walls of said shallow chamber, means for holding it in engagement therewith, an end plate located within the walls of said oven, and means whereby it is retained in close proximity with 55 the inner side of said side plate but separated therefrom, a plate located within said oven and forming in conjunction with the side of the oven next the fire-box and the top of the oven, a circulating flue or passage, said passage being connected with the outer air, all as set forth.

9. The combination in a stove or range of a plate or the like having a recessed edge extending from a shoulder at one corner of the 60 said plate along the front, and continuing around the opposite corner of the plate along the side, with an ornamental band or rim fitting into said recessed edge, the same consisting of two longitudinal sections, the one 65 section fitting into the front recess extending from the shoulder and corner aforesaid to the said opposite corner, and there so combining with the other section fitting into the side recess as to form a design which conceals 70 in whole or in part the joint between them.

10. The combination in a stove or range of a plate or the like, and a band or rim having the longitudinal sections H, H' to form the sides of the edge of said plate, the same being 75 united to each other and to the corner of said plate and shaped at their abutting edges h and h' to form a design which conceals in whole or in part the joint between them.

EDGAR W. ANTHONY.
